UNITED STATES PATENT OFFICE.

GEORGE P. WHITE, OF GLEN ELLYN, ILLINOIS, ASSIGNOR TO DE REMER BLATCHFORD COMPANY, OF CHICAGO, ILLINOIS, A CORPORATION OF ILLINOIS.

FURNACE.

Application filed March 1, 1926. Serial No. 81,461.

My invention relates to a furnace, for heating plates, particularly; or billets or other articles, of the type comprising mechanism whereby the articles are moved 5 through the heating chamber of the furnace by a series of step by step movements by means of a carrier arranged in channels in the hearth of the furnace which carrier is raised to pick up the articles from the 10 hearth, moved forwardly, lowered to deposit the articles in advanced positions on the hearth, and is then moved back through the channels in the hearth to its original 15 position ready for another cycle of movements. A furnace of this character provided with overhead mechanism for raising and supporting the carrier is shown in my co-pending application Serial No. 603,478, filed November 27, 1922.

20 The principal object of the present invention is to provide certain improvements in a furnace of this general type, and more especially in a furnace as shown in my application referred to, the improvements relating particularly to the construction of the longitudinal carrier and of the mechanism by means of which the carrier is raised and lowered and supported in its position above the furnace hearth, whereby the life of the 25 carrier and of this mechanism is prolonged, the power required to operate the moving parts of the conveying apparatus is lessened and such operation made more reliable.

Other objects of the invention will be 30 referred to in connection with the description of the preferred embodiment of the invention illustrated in the accompanying drawings.

In the drawings—

40 Fig. 1 is a plan view of the furnace.

Fig. 2 is a front sectional elevation (the front stock rack being shown in section) on line 2—2 of Fig. 1.

45 Fig. 3 is a transverse vertical sectional view on line 3—3 of Fig. 1.

Fig. 4 is a longitudinal vertical sectional view on line 4—4 of Fig. 1, the doors and their operating mechanisms being omitted from this figure.

50 Fig. 5 is a view, in elevation, of one of the transverse members for supporting the carrier with its vertical guides and part of the mechanism for suspending it from the top of the furnace.

Fig. 6 is a sectional plan taken on line 55 6—6 of Fig. 5 with the scale enlarged.

Fig. 7 is a fragmentary sectional plan view of the furnace on a scale larger than that of Fig. 1.

Fig. 8 is a longitudinal, fragmentary sec- 60 tional view of the carrier.

Fig. 9 is a detail longitudinal view, with parts in section, of the carrier.

Fig. 10 is a cross sectional view on line 10—10 of Fig. 9, and 65

Fig. 11 is a view in elevation, with parts in section, of the front end of the carrier.

Referring to the drawings, 10 designates the hearth of the furnace, 11 the side walls and 12 the arch. The heating chamber 13 70 of the furnace is heated in any suitable way, for example, by means of gas or oil flames introduced through the tuyeres 14 which are preferably arranged in staggered relation at opposite sides of the furnace. Outlet ducts 75 for the products of combustion are indicated at 15. There is an opening into the furnace at each end closed by a door 16 sliding in guides 17 and adapted to be raised and lowered by three chains 18, 19 80 and 20, attached to clips 21 on the upper edge of the door. Chain 18 passes over sheaves 22 and 23 and has attached to the lower end thereof a weight 24. Chain 19 passes over sheaves 25, 26 and is united by 85 a link 27 with chain 20 which passes over sheaves 28 and 29. A chain 30 is connected with link 27 and carries a weight 31 at its lower end. Sheave 23 has connected therewith a lever 32 connected by link 33 with the piston rod 34 of an air cylinder 35 by means of which the door is raised and lowered, weights 24, 31 counterbalancing the 90 weight of the door. It will be understood that this description applies to the door and its operating mechanism at each end of the furnace.

Stock racks 36, 37 are arranged at each end of the furnace approximately at the level of the hearth. These racks may be of identical construction and consist preferably of horizontally arranged channel bars 38 secured at their inner ends to the face plate 39 and at their outer ends to a cross piece 40 supported by uprights 41. 100

The hearth 10 of the furnace is formed with longitudinal panels 42 and the face plates 39 of the furnace with corresponding 105

grooves 43. These channels and grooves are designed to receive the longitudinal members 44 of a carrier or transfer frame by means of which the articles heated in the furnace are given step by step movements from the forward stock rack 36 through the furnace and out upon the rear stock rack 37. The longitudinal members 44 consist preferably of metal pipes which project for some distance out of the furnace at each end. At the forward end of the furnace the pipes 44 are connected by elbows 45 with short vertical pipe sections 46 provided with valves 46^a, the lower ends of which pipe sections are joined by a header 47. This header is made up of a middle section 48 of maximum diameter in the form of a T for admission of cooling fluid through hose connection 49 and on each side of the middle section 48 two sections 48^a, 48^b, of progressively reduced diameter, together with T's 48^c, 48^d and elbows 48^e for connection with the vertical pipe sections 46. The extremities of the pipes 44 at the rear end of the furnace are provided with elbow fittings 50 to which are attached short vertical pipe sections 51 closed by caps 52. The elbow fittings are formed with taps 53 to receive valved elbow-shaped pipes 54 to which are attached flexible tubes 55 for outflow of cooling water at points above the upper inside surfaces of the pipes. These arrangements permit of the circulation of water through the pipes in order to keep the same cool.

The carrier thus formed is raised, lowered and supported in the raised position on three transverse members (the number might be increased for a longer furnace) which are designated 56, 57 and 58, the transverse members 56 and 58 being arranged outside of the furnace at opposite ends thereof and the transverse member 57 in a channel 59 in the hearth 10 of the furnace with its ends projecting out through openings 60 in the side walls 11 (Fig. 3). These transverse members are suspended from the top of the furnace and are simultaneously raised and lowered by mechanism which will be described. The transverse members and their suspended and guiding devices are preferably of the same construction, in each case, this construction being shown in detail in Figs. 5 and 6. 61 is a pipe on which are arranged a series of rollers 62 to support the longitudinal members 44 of the carrier. At each end of pipe 61 is a cross 63 and to these crosses are secured upstanding pipes 64 provided with T fittings 65 to which are secured short horizontal pipe sections 66 provided with flexible hoses 67. To the lower taps of the crosses 63 are secured plugs 68 transversely perforated for a reinforcing member 69 between which and the pipe 61 are arranged

one or more struts 70. The reinforcing member 69 is preferably tubular and its ends are threaded for the nuts 71, the pipe 61 reinforcing member 69 and struts 70 forming together a trussed structure. Water may be circulated through the pipe 61 and upright pipes 64 in order to keep the structure cool. Considerable difficulty has been experienced due to the overheating and bending of the members, as previously constructed, for supporting the carrier bars. The trussed water cooled construction herein provided overcomes these difficulties. If the transverse members become overheated they are likely to bend and sag under the weight of the carrier and its load so as to interfere with or prevent the movements of the carrier. Instead of being water cooled the transverse members may be made of heat resisting metal. The carrier pipes might also be made of such metal.

The ends of pipes 61 are closed by caps 72 and on the short pipe sections 73 of pipe 61 outwardly of the crosses 63 there are arranged rollers 74. These rollers operate between pairs of upright guide members 75. Preferably rollers 76 are mounted on the upper ends of the guides in position to be engaged by the upright pipes 64. Spacers 77, 78, 79, 80, 81, 82, 83, 84 and 85 are arranged between the rollers and the crosses and struts so as to keep the rollers in proper position. Secured to the upper taps of the T's 65 are pipe sections 86 to the caps 87 of which are secured links 88 threaded at their upper ends for an adjustable connection with loops 89 to which the links are attached by nuts 90, 90. The loops are pivotally attached to rock arms on the top of the furnace. There are three of these rock arms 91, 92, 93 one for each of the transverse members 56, 57, 58, the arms being secured to rock shafts 94, 95, 96 turning in bearings 97 on longitudinal beams 98 forming part of the steel framework of the furnace. On the shaft 94 is fixed a lever 99 to which is pivoted the piston rod 100 of a steam or air power cylinder 101, the cylinder being pivoted at its lower end, as indicated at 102 so that it can adjust itself to the movements of the piston rod. Shafts 95 and 96 are provided with arms 103 carrying counterweights 104. The shafts 94, 95, 96 are provided with levers 105, 106, 107 which are pivoted to links 108 so that the operation of power cylinder 101 brings about a rocking movement of all three rock shafts simultaneously.

The longitudinal movements of the carrier are effected as follows: 109 is a power cylinder, the piston rod 110 of which is pivoted at 111 to a lever 112 having a pin and slot connection 113 at its lower end in a clevis 114. The upper end of the lever 112 is formed with a slot 115 to receive the

pin 116 of a clevis 117 secured to a cross beam 118 clamped to the vertical pipes 46 of the carrier.

The longitudinal members 44 of the carrier are preferably provided with means whereby plates, for example, will rest on the carrier at only a few widely spaced points so that the support of the plates by the carrier will interfere as little as possible 10 with the uniform heating of the lower surfaces of the plates. Referring particularly to Figs. 8, 9 and 10, rings 119 are arranged on the pipe 44, and are held in place by spacing sleeves 120 the edge of which 15 fit into rabbets 121 in the rings. Longer sleeves 122 are arranged at the places where the carrier must roll on the rollers 56, 57, 58. All parts are loose to allow for expansion and contraction and to give air 20 spaces tending to keep the parts cool. The sleeves help, in fact, to keep the carrier pipes from being overheated. 123 designates in Fig. 8 a plate resting on the rings 119. The rings are preferably arranged on adjacent 25 pipes in staggered relation, as shown in Fig. 7.

The operation of the furnace as above described, is as follows: A plate, billet or other article is placed upon the forward stock 30 rack 36 and fluid pressure is admitted to cylinder 109 so as to move the carrier in a forward direction, the pipes 44 moving easily over the rollers 62 of the transverse members 56, 57, 58. Fluid pressure is then admitted to the upper end of power cylinder 101 so as to raise the carrier from the channels 42 of the furnace hearth. The carrier picks up the plate or other article from the stock rack and also any article that may be 40 on the hearth of the furnace. The upward movement of the carrier need not be a vertical movement. As shown, the movement will be oblique due to the obliquity of the lever 112 and the pin and slot connection between the lever and the carrier. The lever 45 112 is now moved back (to the full line position, Fig. 4) by application of fluid pressure to the inner end of the cylinder. This gives movement to the carrier by which the plates or other articles on the carrier are 50 advanced toward the rear end of the furnace. A plate near the rear end of the furnace may be carried out above the rear stock rack 37. The carrier is then lowered 55 into the hearth channels depositing the plates on the hearth and stock rack, as the case may be. When an article is to be introduced into the furnace or discharged therefrom, the appropriate door 16 is raised by 60 operation of operating cylinder 35.

The trussed construction of the transverse members and the arrangements for water cooling these members effectually prevent any sagging or bending of the same 65 due to the heat to which said members are

necessarily exposed. By preventing distortion of the transverse supporting members one cause of bending of the carrier bars is eliminated since the carrier naturally conforms itself to the members on which it is supported. The bending of the carrier bars is further checked by the provision of the intermediate transverse member 57 and by the fact that it is water cooled. Water enters the forward header 47 through hose 70 49 and is properly distributed to the pipes 44 by the stepped down diameters of the header sections. The flow of water to the pipes may be further regulated by a proper setting of valves 46a. The water outflows 75 through the water outlets 54 at the rear end of the carrier, the pipes being kept full of water because these outlets open from the upper parts of the pipes. By these arrangements the life of the parts of the mechanism 80 for conveying the articles through the furnace is prolonged, the power required for movement of said parts is lessened, and the operation of the furnace is simplified and 85 made more reliable.

As it is realized that the invention might be embodied in different structural forms, I wish to be understood as claiming all modifications within the scope of the appended 90 claims.

I claim:

1. In a furnace, the combination of a heating chamber having a hearth formed with longitudinal channels and a transverse channel, a carrier comprising members extending through said channels and beyond the heating chamber at opposite ends, transverse members at opposite ends of the heating chamber and a transverse member in 100 said transverse channel on which the carrier members are slidably supported, and means for simultaneously raising and lowering said transverse members.

2. In a furnace, the combination of a heating chamber having a hearth formed with longitudinal channels and a transverse channel, a carrier comprising members extending through said channels and beyond the heating chamber at opposite ends, transverse members at opposite ends of the heating 110 chamber and a transverse member in said transverse channel on which the carrier members are slidably supported, and means suspended from the top of the furnace for simultaneously raising and lowering said 115 transverse members.

3. In a furnace, the combination of a heating chamber having a hearth formed with longitudinal channels and a transverse channel, a carrier comprising members extending through said channels and beyond the heating chamber at opposite ends, transverse members at opposite ends of the heating 125 chamber and a transverse member in said transverse channel on which the carrier 130

members are slidably supported, transverse rock shafts on the top of the furnace provided with arms, connections from said arms to said transverse members, levers on said rock shafts, links connecting said levers, and means for imparting oscillatory movements to the rock shafts.

4. In a furnace, the combination of a heating chamber having a hearth formed with longitudinal channels and a transverse channel, a carrier comprising members extending through said channels and beyond the heating chamber at opposite ends, transverse members at opposite ends of the heating chamber and a transverse member in said transverse channel on which the carrier members are slidably supported, transverse rock shafts on the top of the furnace provided with arms, connections from said arms to said transverse members, levers on said rock shafts, links connecting said levers, rollers on the ends of said transverse members, and vertical guides between which said rollers operate.

5. In a furnace, the combination of a heating chamber, a carrier extending through said heating chamber and projecting out of the same at opposite ends, said carrier comprising a plurality of longitudinally extending members, a stock rack outside of the furnace at each end comprising longitudinally extending spaced supporting members in staggered arrangement with respect to the longitudinal members of the carrier, and means for raising and lowering the carrier and for imparting longitudinal movements to the same in opposite directions whereby articles placed on one of said stock racks may be picked up, carried through the furnace by step by step movements and discharged from the furnace on the other of said stock racks.

6. In a furnace structure having a hearth formed with longitudinal channels and a transverse channel, the side walls of the furnace being formed with openings in line with said transverse channel, a carrier comprising members extending through said longitudinal channels and projecting beyond the ends of the furnace, transverse members outside of the furnace at opposite ends thereof, and a transverse member in said transverse channel and projecting through said openings in the furnace wall for supporting said carrier, guides for the ends of said transverse members, means for raising and lowering said transverse members, and means for imparting longitudinal movements in opposite directions to said carrier.

7. In a furnace structure having a hearth formed with longitudinal channels and a transverse channel, the side walls of the furnace being formed with openings in line with said transverse channel, a carrier com-

prising members extending through said longitudinal channels and projecting beyond the ends of the furnace, transverse members outside of the furnace at opposite ends thereof, and a transverse member in said transverse channel and projecting through said openings in the furnace wall for supporting said carrier, guides for the ends of said transverse members suspended from the top of the furnace, means for raising and lowering said transverse members, and means for imparting longitudinal movements in opposite directions to said carrier.

8. In a furnace, the combination of a heating chamber, a carrier having longitudinal members extending through the heating chamber, and mechanism for raising and lowering said carrier comprising a hollow transverse member on which the longitudinal members of the carrier are slidably supported and which is provided with means for circulation therethrough of a cooling medium.

9. In a furnace, the combination of a heating chamber, a carrier having longitudinal members extending through the heating chamber, mechanism for raising and lowering said carrier comprising a transverse member on which the longitudinal members of the carrier are slidably supported, rollers on the ends of said transverse member, and vertical guides engaged by said rollers.

10. In a furnace, the combination of a heating chamber, a carrier having longitudinal members extending through the heating chamber, mechanism for raising and lowering said carrier comprising a tubular member, rollers on said member for supporting the longitudinal members of the carrier, and spacers for maintaining proper relation between said rollers.

11. In a furnace, the combination of a heating chamber, a carrier having longitudinal members extending through the heating chamber, mechanism for raising and lowering said carrier comprising a tubular, transversely arranged member provided with rollers for the longitudinal members of the carrier, and upright pipes connected to the ends of the tubular member provided with an inlet and an outlet for a cooling medium.

12. In a furnace, the combination of a heating chamber, a carrier having longitudinal members extending through the heating chamber, mechanism for raising and lowering said carrier comprising a tubular, transversely arranged member provided with rollers for the longitudinal members of the carrier, upright pipes connected to the ends of the tubular member provided with an inlet and outlet for a cooling medium, rollers on the extremities of the transverse member, vertical guides between which said rollers operate, and rollers on said

- guides adapted to be engaged by said upright pipes.
13. In a furnace, the combination of a heating chamber, a carrier having longitudinal members extending through the heating chamber, mechanism for raising and lowering said carrier comprising a hollow transverse member provided with means for circulation therethrough of a cooling medium and with rollers for supporting the longitudinal members of the carrier, rollers on the extremities of said transverse member, vertical guides between which said rollers operate, upright members on the ends of said transverse member, and guide rollers on said vertical guides for engagement with said upright members.
14. In a furnace, the combination of a heating chamber, a carrier having longitudinal members extending through the heating chamber, mechanism for raising and lowering said carrier comprising a hollow transverse member on which the longitudinal members of the carrier are slidably supported and which is provided with means for circulation therethrough of a cooling medium, a transverse member provided with rollers for supporting the longitudinal members of the carrier, rollers on the extremities of said transverse member, vertical guides between which said rollers operate, upright members on the ends of said transverse member, guide rollers on said vertical guides for engagement with said upright members, and a bent reinforcing member on the under side of said transverse member and connected with and struttred thereto so as to form a trussed structure therewith.
15. In a furnace, the combination of a heating chamber, a carrier comprising longitudinal members extending through said chamber, a plurality of rock shafts arranged above the furnace, structures for suspending the carrier from said rock shafts comprising, in each case, a tubular member, rollers spaced on said members for supporting the longitudinal members of the carrier, upright pipes at the ends of said tubular member provided with water inlet and outlet, a trussed reinforcement on the under side of said tubular member, rollers on the extremity of said tubular member, vertical guides between which said rollers operate, and rollers on said guides adapted to be engaged by said upright pipes.
16. In a furnace, the combination of a heating chamber and a carrier consisting of a plurality of pipes, a header at one end of the carrier with which said pipes are connected by downwardly extending pipe sections, said header consisting of a middle section of maximum diameter and on each side pipe sections of progressively smaller diameter, a cooling fluid connection with the middle section of the header for admission of cooling fluid to said header, and separate outlet connections with each pipe at the other end of the carrier.
17. In a furnace, the combination of a heating chamber and a carrier consisting of a plurality of pipes, a header at one end of the carrier with which said pipes are connected by downwardly extending pipe sections, said header consisting of a middle section of maximum diameter and on each side pipe sections of progressively smaller diameter, a cooling fluid connection with the middle section of the header for admission of cooling fluid to said header, separate outlet connections with each pipe at the other end of the carrier, and means for controlling the inflow of cooling fluid to the carrier pipes separately.
18. In a furnace, the combination of a heating chamber and a carrier comprising a plurality of longitudinal pipes, a header connecting said pipes, and valves to separately control the flow of cooling fluid as between said header and pipes.
19. In a furnace, the combination of a heating chamber and a carrier comprising a plurality of longitudinal pipes, an inlet header, valves to control the flow of cooling fluid from the header to the pipes and separate outlets at the other ends of the pipes.
20. In a furnace, the combination of a heating chamber and a carrier comprising a plurality of longitudinal pipes, an inlet header, valves to control the flow of cooling fluid from the header to the pipes, and separate outlets at the other ends of the pipes arranged to take cooling fluid from the top part of the pipes.
21. In a furnace, the combination of a heating chamber and a carrier comprising a plurality of longitudinal pipes, and rings on said pipes at spaced intervals.
22. In a furnace, the combination of a heating chamber and a carrier comprising a plurality of longitudinal pipes, rings loosely arranged on said pipes at spaced intervals, and spacing sleeves on the pipes to keep the rings in proper position.

GEORGE P. WHITE.
